COMBINATION LOCK

Giuseppe Prina, Turin, Italy

Application January 3, 1934, Serial No. 705,066
In Italy January 4, 1933

2 Claims. (Cl. 70—53)

This invention relates to a combination lock of the type in which the locking device for the bolt consists of a plurality of combination wheels, which, when they are brought by means of predetermined angular displacements to a certain position, allow the bolt to be operated, while in all the other positions they can possibly assume, the bolt remains locked in the closed position.

The object of this invention is to improve the combination locks of the above mentioned type, in order to increase their safety against picking and at the same time to make them simple and cheap in construction.

According to this invention the bolt is locked in the closed position by means of a number of pawls corresponding to the number of combination wheels and adapted to engage in a notch formed on the bolt. Each of these pawls can be brought to the released position by means of a cam carried by the associated combination wheel.

The cams of the combination wheels are angularly displaced to one another, and to bring them into engagement with the corresponding pawls, it is necessary to rotate the combination wheels through different angles which may be chosen at will.

The combination wheels are enclosed in the lock case and their rotation is effected from the outside by means of a sleeve mounted capable of rotation and axial displacement on a pin carrying at one end the bolt actuating lever and at its other end the operating handle. The sleeve is provided at its inner end with a dowel which can be brought into engagement with one of a plurality of notches formed at the edge of the central hole of the wheels, so that by axially displacing the sleeve its dowel can be caused to engage the notch of the successive wheels to rotate the latter through the desired angle in order to disengage the associated lock pawl from the bolt.

To effect the desired angular displacement of the individual wheels a spring-controlled indicating pawl is provided for each wheel, this indicating pawl co-operating with notches formed at the rim of the wheel. The rotation of the latter causes the indicating pawl to snap into the successive notches of the combination wheel and thus give an indication of the width of the angular displacement of the wheel.

Each wheel is provided at the rim with a tooth engaging a corresponding tooth on the indicating pawl to stop the wheel when the latter is rotated in the opposite direction. This stopping position is the initial position to which all wheels

should be brought in order to effect the rotation through the predetermined angle (a different angle for each wheel) to bring the wheels to the released position.

The position of the cams on the wheels may be varied at will, thereby varying the combination to permit opening of the lock.

A pusher provided on the inner side of the door permits all the lock pawls to be lifted and the bolt to be released, independently of the combination mechanism.

The accompanying drawing shows by way of example a construction of the object of this invention.

Figure 1 shows the lock seen from the inside.

Figure 2 shows on an enlarged scale the combination mechanism in front view and Figure 3 is a partial side view thereof.

Figure 4 is an axial vertical section thereof.

The lock (Fig. 1) consists of a bolt 1 moving in straps or supports 2 on the case P fastened to the door, and engaging in the strap 3 of the plate T fastened to the door frame. The bolt is moved from the outside by means of a lever 4—5 keyed to the pin 6 of the outer handle 7 (Fig. 4) and from the inside by means of the handle 8. The lever 4—5 engages by its end in a socket 9 made of three parts (for simplicity of construction) screwed to the bolt 1 and serving also as stop against the straps 2 in the known manner. The bolt 1 is locked in its closed position by lock pawls 10 engaging a notch 1' therein, (Fig. 2) from which pawls it is released, from the inside, by the spring pusher 11 carried by the plate P and, from the outside, by means of a combination mechanism enclosed in a case formed by two plates 12 connected by distance pieces 13. The pin 6 of the outer handle 7 supports the tubular pin 14 (Fig. 4) operable by means of the knob 15 by rotation on the pin 6. The sleeve 14 carries at its end a dowel 16 movable in a longitudinal slit of the distance tube 17 and engaging in one of the radial notches 18' of the combination wheels 18. Each of these carriers also for each internal notch 18' an outer notch 18'' receiving the spring controlled pawl 19. The sense of rotation of the wheel in which the bolt is released, obtained by means of the sleeve 14, is denoted by the arrow: the number of snaps of the indicating pawl 19 into the notches 18'' indicates the position of the wheel 18 with reference to a determined starting position by rotating the wheel in the opposite direction, until its tooth 18''' engages the tooth 19' of the indicating pawl 19.

Each wheel 18 has a circular shoulder 18a and a

cam 20 on which an arm 10a of a bell crank lever rests under the pressure of a spring, the other arm of the lever being the pawl 10 which locks the bolt 1. When the cam 20 is underneath the 5 arm 10a, which is indicated by the number of snaps of the indicating pawl 19, the bolt is released from the lock pawl 10. A sear-spring 21 serves both for the indicating pawl 19 and the lever 10-10a.

10 As each wheel 18 has its associated pawl 19 and its lever 10-10a, the rotational movement for fully releasing the bolt 1 must be repeated for each wheel (three in Fig. 3) counting for each 15 wheel the respective number of snaps and bringing each time the dowel 16 of the sleeve 14 into engagement with the wheel to be rotated.

Only when all the lock pawls 10 have been lifted, the bolt can be moved by the lever 4-5 operated by means of the handle 7 of the pin 6. 20 Supposing the code is the number 452, and that figure 4 relates to the innermost wheel, 5 to the intermediate wheel and 2 to the wheel nearest the plate P, the knob 15 fully pushed-in is rotated in a direction opposite that of the rotation releasing the bolt until it is stopped, whereupon it is rotated forwardly causing the first indicating pawl 19 to snap four times on the first wheel 18. This brings the first cam 20 under the arm 10a of the first bell crank lever releasing the bolt 30 from the first lock pawl 10. The knob 15 is then displaced longitudinally to a reference mark which denotes the engagement of the dowel 16 with the second wheel 18, for which the process is repeated. The knob 15 is then pulled fully out 35 and the operation is performed for the third wheel, whereby the bolt is released from all the lock pawls 10.

The bolt can be released from the inside by 40 pressing the spring pusher 11 which lifts all the lock pawls (Fig. 2). The cams 20 are screwed to the wheels 18 and by disassembling the mechanism it is possible to displace the cams, for which purpose holes are provided on each notch 18' of the wheel thus changing the individual figure of each wheel.

45 Any attempt to rotate the pin 6 by means of its handle 7 is detected by an electrical indicator. The lever 4-5 is made of two parts (Fig. 1) of which the part 4 is keyed to the pin 6 and the part 5 is articulated at 22 to the former, the oscillation of the part 5 being limited by the engagement of the pin 4' of the part 4 in the slit 5' of the 50 part 5. The spring 23 tends to keep the two parts in alignment. When the part 4 is rocked by the rotation of the pin 6 (handle 7), it operates by its

end remote from the part 5 and through an insulated extension a spring switch carried by the block 24. At each attempt of rotating the handle 7 the toggle 4-5 closes slightly and the switch closes a signalling circuit. A further rotation moves the bolt 1, owing to the engagement 4'-5' between the two toggle elements, only when this is admitted of by the proper combination of the discs 18.

The action of the combination mechanism can 10 be annulled by locking the pusher 11 by means of a suitable device, e. g. of the bayonet type in the "free" position.

What I claim is:

1. A combination lock, comprising a bolt, a plurality of spring-pressed pawls for locking said bolt in its closed position, a plurality of cams, one for each pawl, adapted to release the latter from the bolt, a plurality of wheels on each of which is fixed in an adjustable angular position one of 15 said cams, said wheels being provided at the rim with notches, a spring-pressed indicating pawl which snapping into said notches during the rotation of the wheel, indicates the degree of rotation of the wheel, a pin for operating said bolt, a tubular member rotatably mounted and axially displaceable on said operating pin and a dowel fixed to said tubular member and adapted to be engaged by notches cut on the periphery of the central hole of each wheel for carrying the latter 20 along in rotation to release the corresponding pawl from the bolt. 25

2. A combination lock, comprising a bolt, a pin, a lever fixed to said pin and engaging in a notch on said bolt for operating the latter, a plurality of 30 spring-pressed pawls for locking said bolt in the closed position, a plurality of cams, one for each pawl, adapted to release the latter from the bolt, a plurality of wheels loosely mounted on said pin, on each of which is fixed in an adjustable angular 35 position one of said cams, said wheels being provided at their rim with retaining notches, an indicating pawl for each wheel which by snapping into 40 said notches during the rotation of the wheel indicates the degree of said rotation, a sear-spring 45 for each indicating pawl serving also to maintain the locking pawl in the locked position, a tubular member rotatably mounted and axially displaceable on said pin and a dowel fixed to said tubular member and adapted to be engaged by notches cut 50 at the edge of the central hole of each wheel for carrying along the latter in rotation to release the corresponding pawl from the bolt. 55
